LESLIE JOHN HEATH, OF CAMBRIDGE, MASSACHUSETTS, ASSIGNOR TO B. F. STURTEVANT COMPANY, OF HYDE PARK, MASSACHUSETTS, A CORPORATION OF MASSACHUSETTS.

ECONOMIZER.

Application filed February 28, 1924. Serial No. 695,843.

The present invention relates to fuel economizers and more particularly to economizers designed for withstanding high internal pressures.

5 Fuel economizers are at present commonly constructed of cast-iron, both headers and tubes being of this material. With the increase in pressures under which such devices are now required to operate it has been 10 proposed to use steel in the place of cast-iron in order to secure increased strength, and while the tubes may be very conveniently formed from seamless tubing, difficulty has been experienced in providing 15 headers of this material inasmuch as the wall of tubing is ordinarily too thin to hold the tubes with the necessary rigidity.

The object of the present invention is to 20 provide an economizer of steel construction which has ample strength to withstand the usual modern high pressure conditions, which possesses the requisite rigidity, which is of no greater outside dimensions than those now employed for lower pressures, 25 and which can be manufactured at relatively low cost.

With these objects in view the invention 30 contemplates a construction of economizer having steel tubes and a header formed with a central steel tube about which is cast 35 a body of metal. The central tube of steel provides the necessary strength to resist the high internal pressure, while the surrounding body of cast-metal serves primarily to 40 support the steel tubes and to provide bearing surfaces of sufficient length axially of such tubes to insure a strong and rigid structure.

In the accompanying drawings Fig. 1 is 45 a vertical sectional elevation of an economizer section embodying top and bottom headers; Fig. 2 is a section on line 2-2 of Fig. 1; and Fig. 3 is a section on line 3-3 of Fig. 1.

The illustrated embodiment of the invention 50 comprises a fuel economizer section having a bottom or inlet header 4, a number of parallel economizer tubes 6 of which only two are indicated, and an upper or outlet header 8. In operation the boiler feed water to be heated is circulated from the inlet header through the economizer tubes 6 in parallel, and thence through the outlet header from which it may lead into

other economizer sections or to the boiler 55 through any usual or preferred connections. Hot flue gases are circulated about the tubes 6 in the usual manner for preheating the feed water.

The upper header 8 comprises a seamless 60 square steel tube 10 of substantially the same strength as the parallel economizer tubes, one end of the tube 10 being closed by a mitered cap 12 which is welded to the tube. While the tube 10 may be of any desired shape, it is preferred to use the square form as illustrated in the drawings in order 65 to facilitate the securing of a good joint between such header tube and the economizer tubes without protrusion of the tubes 70 into the interior of the header, thus maintaining a practically unobstructed passage through the header. In order to provide for external connections a round seamless tube 14 is welded at 16 to the square tube 75 10, the welded end of the round tube being compressed at 18 to form a square end which butts against the end of the square tube 10. The header tube is preferably provided at this stage with the openings 80 in its bottom for receiving the economizer tubes and with aligned openings of slightly larger size in its top through which the tubes are to be inserted.

The header tube thus formed is then 85 placed in a mold and a body of iron 20 is cast about the steel tube, brackets 22 and 24 being formed for supporting the header in any convenient manner. By means of suitable cores, the cast-iron body is provided with openings for receiving the tubes 6 and also with tube inserting openings 26 90 registering with the corresponding openings in the header tube 10. It has been found that the presence of the cold steel 95 tube in the mold causes no difficulties either in the pouring of the iron or in the subsequent cooling thereof, the steel tubing being firmly retained within the cast-iron body without appreciable stresses due to shrinkage. 100

After the casting, the several openings in the cast-iron body and in the header tube are machined to size, and the economizer tubes 6 are inserted, from the upper side 105 through the openings 26. The tube receiving openings in the header are machined at 32 with substantially parallel sides, each

tube being provided at its upper end with an enlarged portion 34 which tapers inwardly to a slight degree from top to bottom to provide a tight, steel to steel joint 5 with the header tube. The contact between the upper end of the tubes and the surrounding body of cast-iron, as at 35, while not necessarily steam or water tight is sufficiently close to furnish a firm support for 10 the tubes and to impart the necessary strength and rigidity to the structure. The tubes are provided at their top ends with flanges 30 which seat against the inner face of the tube 10 when the tube is forced to its 15 final position.

The tube inserting openings 26 are made slightly larger than the diameter of the flanges 30 and are machined at 36 with a taper to receive tapered plugs 38. The plugs 20 are inserted into the header through the outlet opening and after being drawn into the openings 26 are secured in position by caps 40 and bolts 42. The fluid pressure during normal operation also acts to seat 25 the plugs tightly within the openings to prevent any leakage.

The lower or inlet header 4 is similar in construction to the upper or outlet header 8, and comprises a square seamless steel 30 tubing 44 closed at one end by a welded riveted cap 46 and welded at the other end to a round inlet tube 48, the whole being surrounded by a body of cast-iron 50. The header tube and its cast-iron body are provided with only one series of openings, viz., the tube receiving openings 52 which are tapered to engage tightly with the tapered lower ends of the tubes 6. Here again it is the steel to steel joint between the 40 header tube and the economizer tube which is relied upon to prevent leakage of steam or water, the contact of the adjacent body of cast-iron with the end of the tube being for the purpose of securing rigidity and 45 strength in the structure. The header 4 also has a supporting bracket 54 similar to the brackets for the header 8.

A complete economizer section comprises the headers 4 and 8, together with a plurality of economizer tubes 6, ordinarily ranging from six to eighteen tubes in the usual construction. In operation the boiler feed water passes successively through the header 4, tubes 6 and header 8. A number of exactly similar economizer sections are usually provided, connections being made between the headers in any convenient manner so that the water may circulate either in series or parallel through the sections. All 60 of the sections are included within a casing through which hot flue gases are passed in contact with the economizer for preheating the feed water.

It will be seen that the central steel header tubes, being of the same material and of

substantially the same strength as the economizer tubes, are not liable to rupture under any pressures which may safely be used on the economizer tubes. The header derives practically its entire strength from the interior steel tubing, the cast-iron body serving to support the central steel tube and hold it rigid and to provide a long bearing joint for each economizer tube so as to hold the latter rigidly in place. The cast-iron body also strengthens the welds between the portions of the steel tubing and provides convenient means for mounting the headers. It also cooperates and assists in the proper positioning and fastening of the 80 closure plugs.

Although the invention is herein illustrated and described in a specific form of fuel economizers, it will be understood that the invention is not necessarily limited thereto but may be employed in other analogous constructions and the forms and proportions of the parts may be varied as desired. Where in the claims the term economizer is employed, this is to be taken to 90 mean any analogous structure.

Having thus described the invention, what is claimed is:—

1. An economizer or the like comprising a pair of separate headers and a plurality of steel tubes connecting the same, each header having a central steel tube to which the first mentioned steel tubes are connected and an enclosing body of cast-metal which surrounds each of the connecting tubes adjacent its end to support the headers and tubes in rigid relation.

2. An economizer or the like comprising a pair of separate headers each having a central tube provided with tube receiving openings and a body of cast-metal surrounding the tube, and economizer tubes entering the tube openings with a tight fit and having supporting contact with the cast-metal body to hold the headers and tubes in rigid relation.

3. An economizer or the like comprising separate headers each consisting of a thin steel tube surrounded by a thick body of cast metal and having openings in the tube and metal to receive the ends of the economizer tubes, and economizer tubes fitted within the openings and engaging the header tubes with a tight taper fit and having supporting contact with the cast metal to hold the headers and tubes in rigid relation.

4. An economizer or the like comprising a header having a substantially square tube provided with tube receiving openings on one side and tube inserting openings aligned therewith on the opposite side, a body of cast metal surrounding the tube and having openings registering with the openings therein, economizer tubes adapted to pass through the tube inserting openings and

with a flange on the following end to engage the inner face of the header tube, the end of the economizer tube making a tight joint with the header tube, and being supported by the body of cast metal, and closures for the tube inserting openings.

5. A header for economizers and the like

comprising a thin central steel tube having an opening for receiving an economizer tube, and a thick body of cast-iron surrounding the tube and the opening to provide a support for the end of the economizer tube to hold the tube and header in rigid relation.
